UNITED STATES PATENT OFFICE.

LOUIS HEISER, OF NEW HAVEN, MICHIGAN.

BEET-HARVESTER.

No. 894 001.

Specification of Letters Patent.

Patented July 21, 1908.

Application filed April 6, 1908. Serial No. 425,312.

To all whom it may concern:

Be it known that I, LOUIS HEISER, a citizen of the United States of America, residing at New Haven, in the county of St. Clair and State of Michigan, have invented certain new and useful Improvements in Beet-Harvesters, of which the following is a specification, reference being had therein to the accompanying drawings.

10 This invention relates to beet harvesters and consists in the matters hereinafter set forth, and more particularly pointed out in the appended claims.

In the drawings, Figure 1 is a view in side elevation, with parts broken away, of a beet harvester embodying features of the invention. Fig. 2 is a view in front elevation of the machine with portions of the mechanism omitted to give clear view of the topping means. Fig. 3 is a view in rear elevation of the machine, with the topper omitted. Fig. 4 is an enlarged view in detail of a topper driving mechanism. Fig. 5 is a view in detail of a topping knife. Fig. 6 is a view in detail of a share beam clevis pin plate.

Referring to the drawings, 1 indicates a substantially rectangular main frame, whose forward end is carried on a caster wheel 2 journaled in an upright fork 3, whose stem 4 turns in a guide bracket 5, and is rigidly connected to a pole 6. The body of the frame is supported on a pair of parallel upright stems 7 longitudinally adjustable in guide brackets 8 by means of properly disposed links 9 and independent levers 10 having latches 11 locking with quadrants 12, splines 13, keys or the like preventing rotation of the stems in the brackets. A traction bearing wheel is journaled on a stub axle 14 or stud on each stem.

One of the traction wheels 15 carries a sprocket wheel 16 connected by a chain 17 and sprocket pinion 18 to a horizontal shaft 19. A bevel gear 20 secured on the end of the shaft meshes with a bevel pinion 21 on an upright spindle 22, a key or spline 23 thereon permitting longitudinal movement of the spindle through the pinion, a main bearing 24 on the frame, and a lower bracket 25 held by a side brace 26. A horizontal cutting knife 27 having substantially radial blades 28 is made fast to the lower end and a fly or balance wheel 29 is secured to the upper end of the spindle. The sprocket wheel 16 preferably has a ratchet connection, not shown, of

any standard type, with the hub of its traction wheel, so that the knife may be rotated by the balance wheel when the traction wheel is momentarily arrested. The spindle 22 is vertically adjustable by a latch lever 30 interlocking with a quadrant 31, and having a link 32 and curved fork bar 33 embracing a flanged collar 34 on the spindle, the fork bar riding on a cross-brace 35 of the main frame and acting as a rear brace to the spindle. 65

The other traction bearing wheel 36 is operatively connected through a sprocket wheel 37 secured to its hub, a chain 38 and pinion 39 to a horizontal crank shaft 40 journaled near each end in a bearing 41 on the outer end of an arm 42 pivoted at its inner end 43 to the back end of the main frame 1, a rock arm 44, links 45 and latch lever 47 engaging a quadrant 48 affording vertical adjustment of the shaft. 70

A plurality of tedder forks 49 having blunt or bulbous ended prongs 50 are pivoted between their ends on the several cranks 51 of the shaft 40 and at their upper extremities to the outer ends of links 52 hung at their inner ends to the frame. The several cranks of the shaft 40 are offset in proper angular relation to operate the forks in order. 75

The lifting or pulling means consists of a properly shaped share 53 rigidly connected to the lower end of a goose neck 54 pivoted near its bend on a cross-bolt 55 to a cross-member of the main frame, the horizontal end extending loosely through a stirrup 56 at the front end of the frame and having a segmental plate 57 with a series of apertures 58 whereby the clevis pin of a cross-tree may be secured. The share 53 is centrally arranged between the traction bearing wheels while the topper knife is offset therefrom, so that 95 the share runs to one side of the row the knife is topping.

In operation, the draft is applied directly to the share whose depth of furrow is regulated by adjustment of the frame vertically on the traction wheels, so that the main resistance is not communicated to the frame. The knife with its steadyng balance wheel slices the tops off and throws them to one side, while the tedder forks, adjusted to penetrate slightly below the loosened dirt thrown up by the share, kick the loosened beets out and leave them on the top of the ground ready for loading. 100

It is to be understood that the usual lubri- 110

cating and adjusting means are provided, although not shown, the details of construction following the lines of good practice.

Obviously, changes in the details of construction may be made without departing from the spirit of the invention and I do not care to limit myself to any particular form or arrangement of parts.

What I claim as my invention is:

- 10 1. In a beet harvester, the combination of a main frame whose forward end is carried by a caster guide wheel and whose body is supported by a pair of traction bearing wheels independently adjustable vertically therein, with a rotatable cutter vertically adjustable in the frame operated by one of the traction wheels, a lifting share between the traction wheels carried by a goose neck draft beam pivoted between its ends to the frame and provided at its forward end with means for securing a draft rigging thereto, and a gang of oscillating tedder forks to rear of the lifter driven by the other traction wheel.
- 15 2. In a beet harvester, the combination of a main frame whose forward end is carried by a caster guide wheel and whose body is supported by a pair of traction bearing wheels independently adjustable vertically therein with a rotatable cutter vertically adjustable in the frame operated by one of the traction wheels, means to raise and lower the cutter, a lifting share between the traction wheels carried by a goose neck draft beam pivoted between its ends to the frame and provided at its forward end with means for securing a draft rigging thereto, a gang of oscillating tedder forks to rear of the lifter driven by the other traction wheel, and adjusting means adapted to raise and lower the fork gang bodily in the frame.
- 20 3. In a beet harvester, the combination of a main frame whose forward end is carried by a caster guide wheel and whose body is supported by a pair of traction bearing wheels independently adjustable vertically therein, a rotatable spindle vertically adjustable in the frame, a knife having substantially ra-

dial blades secured to the lower end thereof, a balance wheel on the upper end of the shaft, a horizontal shaft operatively connected by chain and sprocket to one of said traction bearing wheels, a bevel gear thereon, a bevel pinion meshing therewith having non-rotatable sliding engagement with the spindle, a lifting share between the traction wheels carried by a goose neck draft beam pivoted between its ends to the frame and provided at its forward end with means for securing a draft rigging thereto, and a gang of oscillating tedder forks to rear of the lifter driven by the other traction wheel.

4. In a beet harvester, the combination of a main frame whose forward end is carried by a caster guide wheel and whose body is supported by a pair of traction bearing wheels independently adjustable vertically therein, a rotatable spindle vertically adjustable in the frame, a knife having substantially radial blades secured to the lower end thereof, a balance wheel on the upper end of the shaft, a horizontal shaft operatively connected by chain and sprockets to one of said traction bearing wheels, a bevel gear thereon, a bevel pinion meshing therewith having non-rotatable sliding engagement with the spindle, a flanged collar fixed on the spindle, a curved fork engaging the collar, bearing and sliding on the main frame, a quadrant latched lever on the frame, a link actuating the upper end of the fork and the lever, said parts being adapted to shift the spindle vertically in the frame, a lifting share between the traction wheels carried by a goose neck draft beam pivoted between its ends to the frame and provided at its forward end with means for securing a draft rigging thereto, and a gang of oscillating tedder forks to rear of the lifter driven by the other traction wheel.

In testimony whereof I affix my signature in presence of two witnesses.

LOUIS HEISER.
